UNITED STATES PATENT OFFICE.

JOHN F. KELLOGG, OF GUTHRIE, OKLAHOMA.

ORE-CONCENTRATOR.

1,314,335.

Specification of Letters Patent. Patented Aug. 26, 1919.

Application filed March 13, 1918. Serial No. 222,186.

To all whom it may concern:

Be it known that I, JOHN F. KELLOGG, a citizen of the United States, residing at Guthrie, in the county of Logan and State 5 of Oklahoma, have invented certain new and useful Improvements in Ore-Concentrators, of which the following is a specification.

This invention relates to ore concentrators 10 and while primarily designed for use in the separation of ores containing lead and zinc, the concentrator may be employed also in the separation of gold bearing ores.

It is one aim of the present invention to 15 provide an ore concentrator which will, in operation, permit of the recovery of a maximum percent of the valuable mineral content of the ore and to provide means whereby the separator may be adjusted so that a 20 negligible quantity only of valuable minerals will be lost in the chats and consequently so that the valuable portion of the ore separated will be of maximum richness in its mineral content.

Another aim of the invention is to provide 25 an ore concentrator so constructed that the same will require little attention in its operation and will be continuous in its operation, the valuable portion of the ore being separated and continuously carried off 30 through one outlet and the chats being permitted to escape through a separate outlet.

Another aim of the invention is to provide 35 an ore concentrator which will be of maximum efficiency in its operation whether the same be employed in treating the ores in a dry state or mixed with water, the concentrator being therefore adapted for use under practically all conditions and not depending 40 for its successful operation upon the presence of water in the vicinity in which it is operated.

The invention also has as its object to provide 45 a concentrator, which by a slight modification in its structure, may be adapted for the separation of gold bearing ores instead of lead and zinc ores.

The invention also has as its object to so 50 construct the concentrator that the same may be employed when mining for placer gold in which event the concentrator will be adapted to not only separate the gold but also to separate the so called black or steel sand which in itself has a certain value be- 55 cause of its mineral content.

In the accompanying drawings:

Figure 1 is a vertical transverse sectional view through the concentrator embodying the present invention constructed and arranged for use in the separation of lead and zinc ores;

Fig. 2 is a front elevation of the concentrator;

Fig. 3 is a top plan view of the concentrator, the feed pipe being shown in section;

Fig. 4 is a plan view of the mechanism provided for imparting panning motion to the pan supporting bed of the concentrator;

Fig. 5 is a vertical transverse sectional view illustrating the pan of the concentrator and a modified form of distributor head designed for use in connection with the pan in the separation of gold bearing ores;

Fig. 6 is a top plan view of a portion of the distributor head shown in Fig. 5 of the drawings.

The concentrator embodying the present invention consists, briefly stated, of a bed to which a panning motion is imparted, a concentrating pan supported upon the bed, a distributor head arranged above the pan and designed to supply the crushed ore to the pan, evenly distributed, and an adjustable gate designed to control the discharge of the separated valuable mineral content of the ore from the pan. The elements above mentioned are mounted in a suitable framework of open construction which framework may be built of angle iron or any other suitable material and which is indicated in general by the numeral 1. Suspended within the framework 1 from each upper corner thereof for free oscillatory motion is a rod 2 and these rods at their lower ends are loosely connected as at 3 with the lower ends of legs 4 which are secured to the under side of the pan bed and are braced by means of braces 5 also secured to the said under side of the bed. The pan supporting bed is indicated in general by the numeral 6 and the same comprises a shallow inverted conical body provided centrally with a relatively large opening 7 and at its periphery with an upstanding flange 8. At this point it will be understood that the pan supporting bed 6 is supported by the rods 2 in a manner to permit of its oscillation and in order that a panning motion may be imparted to the said bed, means is provided which will now be described. The numeral 9 indicates a

105
110

shaft which is rotatably mounted in suitable bearings 10 upon a supporting frame structure 11 mounted within the frame 1, and this shaft carries bevel gears 12 which mesh 5 with similar gears 13 at the lower ends of shafts 14 rotatably mounted in suitable bearings at opposite sides of the vertical axis of the pan supporting bed 6. The shafts 14 at their upper ends carry crank disks 15 having upwardly projecting crank pins 16 which work in bearings 17 mounted upon a depending flange 18 carried by the bed 6 and surrounding the opening 7. Power is applied 10 to the shaft 9 in any suitable manner and through rotation of this shaft, an oscillatory motion is imparted to the pan supporting bed in a manner closely resembling the motion which a miner will give to his pan in washing for gold. It will be understood, 15 however, that various types of mechanism could be provided for imparting such motion to the said bed 6 and that, therefore, I am not to be limited to the use of the specific means herein shown and described.

20 25 The concentrating pan of the apparatus is indicated in general by the numeral 19 and the said pan is of shallow inverted conical form and is provided at its periphery with an upstanding flange or rim 20. The pan is disposed upon the bed 6 with its rim 20 seating within the flange 8 of the said bed, and at its central portion the pan is formed 30 with a discharge opening 21 and surrounding this opening is a depending discharge 35 spout portion 22 which is preferably cylindrical and from which leads a discharge pipe 23. The bottom of the spout portion 22 is closed except for a threaded opening 24 into which is threaded one end of a discharge pipe 25 which end of the pipe extends 40 upwardly within the said spout 22 in the manner clearly shown in Fig. 1 of the drawings. The lower end of the pipe 25 leads downwardly and may discharge at 45 any convenient point. As will be presently explained, the valuable mineral content of the ore is to be discharged through the opening 21 and into the spout 22 and finally through the pipe 23 whereas the chats are 50 to be delivered from the concentrator through the pipe 25.

55 60 As heretofore stated a gate is provided for controlling the discharge of the valuable mineral content of the ore from the concentrator and this gate, which is indicated in general in the drawings by the numeral 26, comprises a tubular neck 27 which is fitted for vertical sliding adjustment in the upper end of the pipe 25 and which is provided at its upper end with a head 28. The head 28 surrounds the said upper end of the tubular neck 27 and is of shallow conical form and the outer edge or periphery of this head is designed, in the vertical adjustment of the 65 neck 27, to be positioned a greater or less

distance above the upper or concave surface of the concentrating pan 19. In order that the gate 26 may be adjusted in the manner and for the purpose stated, a stem 29 is fixed at its upper end within the neck 27 and 70 extends downwardly through the upper end of the pipe 25 and fits slidably through a suitable stuffing box 30 formed in the end of the pipe. The lower end of the stem 29 is pivotally connected as at 31 with an adjusting lever 32 which at one end is connected to a link 33 preferably extending downwardly from the flange 18, and the other end of the said lever is pivoted to the lower end of a threaded stem 33' which may 80 be adjusted vertically by the rotation of a hand wheel 34 to raise and lower the lever 32 about its pivot so as to adjust the said gate 26.

In order that the crushed ore may be fed 85 to the concentrating pan in an evenly distributed manner, there is provided a distributor head which is indicated in general by the numeral 38 and this head is of shallow conical form and is supported in any 90 suitable manner immediately above the pan 19, as for example by means of suitable brackets 39 depending from the lower end of a feed pipe 40 through which the crushed ore is delivered onto the said head 95 38 at the apex thereof. The head 38 is of less diameter than the pan 19 and is positioned substantially concentric with relation to the said pan.

100 As concerns the form of concentrator above described, the operation thereof is as follows: The crushed ore is delivered through the feed pipe 40 onto the apex of the distributor head 38 and will flow or slide down the sloping surface of this head and will 105 pass over the edge or rim thereof and thus reach the upper surface of the concentrating pan 19 substantially at the outer periphery of the said pan. In the meantime the means provided for imparting panning motion to the pan supporting bed has, of course, been 110 set in operation and therefore due to the peculiar motion given the pan, the crushed ore will gradually flow down the surface of the pan toward the central portion thereof. During this operation the heavier particles 115 which, of course, are the particles bearing the lead and zinc content of the ore, will not settle until they form a bottom stratum resting directly upon the surface of the concentrating pan, the chats, being lighter, forming an upper stratum as will be readily understood. The gate 26 having been properly adjusted, the valuable mineral particles which have settled by gravity will pass beneath the edge of the gate, or in other words, 120 through the space between this edge and the upper surface of the concentrating pan and will finally pass through the opening 21, into the spout 22 and out through the pipe 23 125 130

into any suitable receptacle or pile. On the other hand the chats or lighter particles will gradually rise along the upwardly sloping surface of the head 28 of the gate 26 and 5 will finally pass downwardly through the neck 27 and out through the pipe 25. It will now be understood that should the ore be very rich in its lead or zinc content, the stratum consisting of this content will be 10 considerably thicker or deeper than if the ore is relatively poor in its mineral content and therefore in the former instance the lever 32 would be manipulated so as to elevate the gate 26 to position the edge of the head 15 28 a suitable distance above the surface of the pan 19 to permit of the freer passage of particles beneath the head or past the gate, and in the latter instance the lever would be manipulated to lower the gate 26 20 so as to permit the passage only of the relatively thin or shallow stratum of valuable mineral particles. Thus having ascertained in the first instance approximately the percentage of valuable metal contained in the 25 ore, the lever 32 may be adjusted so as to permit of the passage past the gate 26, of only that portion of the bulk of the crushed ore which consists of the metal bearing particles and therefore practically the entire 30 valuable mineral content of the ore may be recovered and there will be a minimum waste discharged with the chats. While the embodiment of the invention above described and illustrated in Figs. 1 to 4 inclusive, is 35 especially designed for use in the separation of lead and zinc bearing ores, nevertheless it may be successfully employed in the separation of ores bearing other heavy metals. Where, however, gold bearing ore is to be 40 treated, I prefer to employ the form of distributing head clearly shown in Figs. 5 and 6 of the drawings and which head will now be described.

The distributing head shown in the said 45 figures is indicated in general by the numeral 41 and the said head while substantially of shallow conical form, nevertheless has its upper surface formed with a series of successively elevated annular step portions 50 42, these portions being concentrically arranged as will be apparent by reference to Fig. 6 of the drawings. A shallow riffle 43 projects upwardly from the outer edge of each portion 42 and extends continuously 55 around the same and in each portion 42 there is formed an annular series of pockets 44 which pockets are of inverted conical form and of a suitable depth determined best by experiment. The apex of the distributing 60 head is substantially circular and flat as indicated by the numeral 45 and is formed centrally with a relatively large pocket 46 of the same general shape, however, as the pockets 44, and surrounding this apex is a 65 shallow riffle 47. Whereas in the instance

of the distributor head described in connection with the concentrator as adapted for use in the separation of lead and zinc ores, the said head is relatively fixed and consequently is not subjected to the same motion 70 as the pan supporting bed, in the instance of the distributor head just described above, the same is either fixedly supported upon the pan supporting bed or upon the pan itself so that when the panning motion is imparted 75 to the bed, the distributing head will likewise be given such motion. It will now be understood in connection with this embodiment of the invention that as the crushed ore is deposited onto the head at the apex 80 45 thereof, it will gradually flow over the riffle 47 and the riffles 43 descending along the series of stepped portions 42 and passing over the pockets 44. In this operation the heavier gold bearing particles will settle 85 upon the stepped portions 42 and the major portion thereof will be collected in the pockets 44, and some in the pocket 46 so that the material finally discharged over the outer edge of the distributing head and onto 90 the concentrating pan will contain little if any gold. Where this embodiment of the invention is employed in placer gold mining, the concentrating pan and gate heretofore described will prove highly efficient in 95 separating the so called black or steel sand which is heavier, of course, than the dirt or chats of the ore. This sand could after collection, be again treated for the purpose of recovering therefrom new gold or platinum 100 contents. Also this embodiment of the invention may be employed effectually in the vicinity of quartz mills, the distributing head serving to recover the free gold, and the concentrating pan and gate constituting 105 110 a means for recovering the remaining gold content of the quartz which would be subsequently treated to a cyaniding process.

Having thus described the invention, what is claimed as new is:

1. In an ore concentrator, a concentrating pan, means for imparting panning motion thereto, the said pan having a concave upper surface and being formed at the low point in its surface with a discharge opening, a discharge pipe extending up through the opening and having an open upper end, and a gate surrounding the upper end of the said pipe extending laterally therefrom and having its outer edge spaced above the said 115 surface of the pan and surrounding the opening therein.

2. In an ore concentrator, a concentrating pan having a discharge opening, a gate consisting of a plate disposed above and across the opening with its outer edge spaced above the surface of the pan and surrounding the opening, and means for vertically adjusting the said gate concentrically with the discharge opening in the pan.

3. In an ore concentrator, a concentrating pan, means for imparting panning motion thereto, the said pan having a concave upper surface and being formed at the low point in its surface with a discharge opening, a discharge pipe extending up through the opening and having an open upper end, a gate surrounding the upper end of the said pipe and having its outer edge spaced above the 10 said surface of the pan and surrounding the opening in the pan, and means for adjusting the said gate whereby to vary the distance between the said edge of the gate and the said surface of the pan.
- 15 4. In an ore concentrator, a concentrating pan, means for imparting panning motion thereto, the said pan being provided with a discharge opening, a shallow conical gate arranged above the said opening with its 20 outer edge spaced above the surface of the pan and surrounding the said opening, the gate being provided with a discharge opening through its apex, and means for adjusting said gate vertically concentric with the 25 discharge opening in the pan.
5. In an ore concentrator, a concentrating pan, means for imparting panning motion thereto, the said pan being provided with a discharge opening, a shallow conical gate arranged above the said opening with its 30 outer edge spaced above the surface of the pan and surrounding the said opening, a discharge opening being formed through the
- 35
- apex of the gate, and means extending through the discharge opening in the pan for adjusting the gate to vary the distance between its said edge and the said surface of the pan.
6. In an ore concentrator, a distributing head of approximate conical form and having 40 a series of concentric relatively stepped surfaces and an upstanding riffle at the outer margin of each surface, the stepped surfaces of the distributing head being each formed with an annular series of pockets.
7. In an ore concentrator, a concentrating pan having a continuous concave upper surface and formed at its lowest point with a constantly open outlet, means for imparting panning motion to the pan, means for supplying material to the pan at the outer portion thereof, a discharge pipe extending up into the outlet in the pan and spaced from the walls of the same, the upper end of the pipe extending above the said lower portion 55 of the pan and being constantly open, and a shallow conical gate carried by and surrounding the open upper end of the said discharge pipe and having its outer periphery spaced above the said upper surface of the 60 pan and surrounding the outlet in the pan.

In testimony whereof I affix my signature.

JOHN F. KELLOGG. [L. s.]
